DESIGN FOR A TRAY

Henry Herzog, Lincoln, Nebr.

Application October 6, 1945, Serial No. 122,605

Term of patent 14 years

(Cl. D44—10)

To all whom it may concern:

Be it known that I, Henry Herzog, a citizen of the United States, residing at Lincoln, in the county of Lancaster and State of Nebraska, have invented a new, original, and ornamental Design for a Tray, of which the following is a specification, reference being made to the accompanying drawing, forming part thereof, and in which

I claim:

The ornamental design for a tray, as shown.
HENRY HERZOG.
